(57) **CLAIM**

The ornamental design for a guitar, as shown and described.

DESCRIPTION

The file of this patent contains at least one drawing executed in color. Copies of this patent with color drawings will be provided by the Office upon request and payment of the necessary fee.

FIG. 1 is a perspective view of a first embodiment of a guitar showing our new design;

FIG. 2 is a front elevational view thereof;

FIG. 3 is a bottom plan view thereof;

FIG. 4 is a top plan view thereof;

FIG. 5 is a left side elevational view thereof;

FIG. 6 is a right side elevational view thereof;

FIG. 7 is a front elevational view of a second embodiment of the guitar;

FIG. 8 is a left side elevational view thereof;

FIG. 9 is a top-front perspective view thereof; and,

FIG. 10 is a partial view thereof, showing the guitar body and lower neck.

A broken line disclosure is understood to be for illustrative purposes only and forms no part of the claimed design.

**1 Claim, 8 Drawing Sheets
(4 of 8 Drawing Sheet(s) Filed in Color)**
